UNITED STATES PATENT OFFICE.

WAYNE A. DUNCAN, OF CHICAGO, ILLINOIS.

STEAM-COOKER.

1,331,005.

Specification of Letters Patent. Patented Feb. 17, 1920.

Application filed August 14, 1919. Serial No. 317,535.

To all whom it may concern:

Be it known that I, WAYNE A. DUNCAN, a citizen of the United States, residing at Chicago, in the county of Cook and State 5 of Illinois, have invented certain new and useful Improvements in Steam-Cookers; and I do hereby declare the following to be a full, clear, and exact description of the invention, such as will enable others skilled in 10 the art to which it appertains to make and use the same.

This invention relates to a steam cooker of the type illustrated in my pending application, Serial No. 245,318, filed July 17, 15 1918, and particularly to the door construction thereof.

The primary object of the invention resides in the provision of a door which will, when in its closed position, prevent the escape 20 of steam or heat from the cooking compartment, and yet one which may be readily opened and closed in the minimum time.

In the drawing:

25 Figure 1 is an elevation of my invention; Fig. 2 is a fragmental section thereof; and Fig. 3 is a fragmental elevation.
A portion of the cooking chamber is illustrated 30 and this comprises inner and outer shells 5 and 6, the edge 7 of the outer shell 6 at the door opening extending beyond the edge 8 of the inner shell 5 for a purpose which will later appear. A channel member 35 9 extends completely around the door opening and is secured to the edges 7 and 8 of the shells 5 and 6 by turned over portions 10 and 11. This channel member is backed up by a reinforcing member 12, preferably 40 of bar metal, which is disposed between the shells 5 and 6 as illustrated in Fig. 2 of the drawing. A gasket 13 of rubber or other suitable packing material is disposed in the channel member 9 and because of the difference 45 in extent of the inner and outer shells 5 and 6, a portion of the gasket is exposed at 14.

A sheet metal door 15 is hinged to one side of the outer shell 6 at 16 and is adapted 50 to close against the gasket 13, as illustrated in Fig. 2 of the drawing. The spacing of the inner edge of the channel member 9 from the door results in a free space 17 for the compression of the gasket.

55 A plurality of plates 18 are secured to the sides of the outer shell and each of these

plates is provided with an opening 19 for the accommodation of a ball 20 on the end of an arm 21. These balls 20 extend into the space between the shells 5 and 6 and 60 act as pivots for the arms 21. Angular portions 22 are formed on the arms 21 and are adapted to swing to overlie the edges of the door at intervals around the same, as illustrated in Fig. 1.

65

A thumb screw 23 extends through each angular portion 22 and is adapted to be screwed against the edge of the door to force the same against the gasket 13. The pressure exerted by the screws 23 causes the 70 compression of the gasket and particularly that portion of the gasket located adjacent to the space 17. The result of this local compression is the binding of the gasket, not only against the inner face of the door 75 itself, but also against the side and bottom walls of the channel member.

It will be appreciated that when it is desired to open the door it is only necessary to back off the screws 23 and swing the arms 80 21 about their pivots to free the door. When the door is swung to its closed position it abuts against the gasket 13. The arms 21 are then swung into position and the screws 23 tightened. The tightening of these 85 screws compresses the gaskets 13 and binds the same against the door and the walls of the channel member 9 whereby a toggle joint is formed.

It will be observed that the ball elements 90 20 bear against one side of the reinforcing elements 12 so that when the thumb screws 23 are tightened there is a direct binding action between the screw and the ball member, thus relieving the strain on the shells 95 5 and 6.

What I claim is:

1. In a cooker having inner and outer shells, a channel member mounted at the edges of and between said shells, the inner 100 wall of said channel member being shorter than the outer wall, a compressible gasket mounted in the channel member, the outer face of the gasket extending slightly beyond the edge of the outer wall of the channel member, a door hinged on the outer shell, and means adapted to exert pressure on the door at points between the inner and outer walls of the channel member.

2. In a cooker having inner and outer 110 shells, a channel member mounted at the edges of and between the said shells, the

inner wall of the channel member being shorter than the outer wall thereof, a rectangular compressible gasket in the channel member, the outer face of the gasket extending slightly beyond the edge of the outer wall of the channel member, whereby a portion of the gasket extends beyond the edge of the inner wall, a door hinged to the outer wall and adapted to abut against the

outer edge of the channel member, and means adapted to exert pressure against the gasket between the inner and outer walls of the channel member, whereby the gasket is caused to bind against the door and the walls of the channel member.

In testimony whereof I affix my signature.

WAYNE A. DUNCAN.
